UNITED STATES PATENT OFFICE.

JOHN L. DINSMOOR, OF NEW YORK, N. Y.

SEALABLE PACKAGE TIE.

Application filed September 20, 1924. Serial No. 738,748.

To all whom it may concern:

Be it known that I, JOHN L. DINSMOOR, a citizen of the United States, and a resident of New York, borough of Manhattan, in the county of New York and State of New York, have invented certain new and useful Improvements in Sealable Package Ties, of which the following is a specification.

This invention relates to sealable package ties, and has for its object to provide a device of the character specified, simple in construction, easily applied and adapted to be sealed by any one of a number of known means. Other objects will appear later herein.

My improvements comprise features illustrated in their preferred embodiment in the drawing accompanying this specification, wherein:

Figure 1 shows my improved tie formed of wire with three eyes therein. Fig. 2 shows the tie of Fig. 1 bent into circular form ready for application to a package. Fig. 3 shows the tie of Figs. 1 and 2 with the shanks of the terminal eyes twisted together ready for the reception through all three eyes of a locking device. Fig. 4 is similar to that of Fig. 3 and showing the tie drawn snugly about the neck of a bag and sealed by means of a flat sealing strip passed through the three eyes of said tie. Fig. 5 is a modified form of my device. Fig. 6 shows the form of Fig. 5 assembled, as when about a package or bag neck. Fig. 7 shows the same form as Fig. 6 with locking strip attached. Fig. 8 shows another modification. Figs. 9, 10 and 11 show steps and a mode of assembling and locking the modified form of Fig. 8.

In the preferred form of Fig. 1, my improved tie preferably comprises a flexible member 2, made from wire, provided at the ends with eyes 3, 4, respectively, and, if intended for use with a flat sealing strip, such as shown in Fig. 4, said eyes are preferably oblong, as shown. Said eyes may be formed in any convenient manner, as by flattening and expanding the metal, as eye 3, or by twisting the end of the wire about the body thereof, as eye 4. In case the twisted wire form is used it is required that the twisted portion be of sufficient length to make said twisted portion or portions secure against being tampered with when in sealable position about a package. By experience I have

found that three or more turns is efficient for the purpose. Near one end of said tie, Fig. 1, I preferably form a third eye 5, from a bight of said member 2, by twisting the two strands of the bight as shown.

In applying the tie to a package, the body portion 2 is wrapped about the package, Fig. 4, and those portions of said body adjacent the end eyes are twisted together, thereby drawing the tie taut about the package. Then sealing means comprising a strip of material, such as a flat piece of metal 6, Figs. 4 and 7, or a wire or cord 7, Fig. 11, is passed through the two assembled end eyes 3 and 4 and through the third eye 5.

In the modification of Fig. 5, the body portion 8 may be of cord or wire, the length of which is about twice that of the finished tie. The end portions thereof are twisted about the midportion until the ends 9 and 10 of said end portions meet and preferably overlap and where they are preferably sealed or brazed, as the material calls for, opposite eyes 11 and 12 being left open in opposite ends of said tie. This modification is applied to the package by being wrapped around the package and being drawn taut thereabout by twisting together those portions of the tie adjacent said eyes, Fig. 6, and then folding down toward the body 8 of the tie said assembled eyes. Sealing means comprising a strip of material, as 6, Fig. 7, is then passed through the assembled eyes 11, 12 and about the body portion of the tie. Said sealing strip is preferably, for convenience, slipped under the body of the tie before the tie is drawn taut.

In the modification of Figs. 8, 9, 10 and 11, the general form of Fig. 1, with the omission of the third eye, is employed. The length of the tie in this modification is relatively longer than in the other forms shown, for a wider range of adjustment. In applying, the body portion 13 is wrapped about the package and one eye end, as 15, is passed through the other eye, as at 14, and said eye at 15 is folded back to the right, Fig. 9, and laid against the body of the flexible member 13. Then a bight 16 is formed in said member 13 adjacent said eye at 15, and said bight is twisted to form an eye 17 therein and at the same time, or thereafter, the shank 18 of said eye at 15 is twisted together with the shank of bight eye 17, Fig. 10, whereby the tie is drawn taut about the

package. The two eyes 15, 17, thus assembled, are bent toward the body 13 of the tie and sealing means comprising a strip of material, as 7, is passed through the two eyes 5 and about the adjacent portion of the body 13 of the tie.

It will be obvious that the assembled eyes 15, 17 may with equal efficiency be folded to the left in Fig. 10 and the sealing strip 10 passed through said eyes and through eye 14, instead of as shown in Fig. 11.

There is thus provided a simple and efficient sealable package tie, easily applied and effective in operation.

15. The term sealable tie, as herein used, will be understood to mean a tie having at least one closed loop or eye through which a sealing strip may be passed for locking by enclosure with another portion of said tie.
20. The term package as herein used will be understood to include a box, bale, bag or other article or container adapted to be encircled and sealed.

I claim:

25. 1. A sealable package tie including in combination a flexible member having an eye formed in each end thereof, said member being adapted for encircling a package and being drawn taut thereabout by twisting 30 together the portions thereof adjacent said eyes, and sealing means comprising a strip of material passed through said eyes and

about a single portion of said member and means for sealing the strip of material.

2. A sealable package tie including in combination a flexible member having an eye formed in each end thereof, a third eye formed from a bight of said flexible member between said end eyes, said member being adapted for encircling a package and being drawn taut thereabout by twisting together the portions thereof adjacent said end eyes, and sealing means comprising a strip of material adapted to be passed through said eyes and said bight eye for sealing the tie.

3. A sealable package tie including in combination a flexible member having an eye formed in each end thereof, said member encircling a package and being drawn taut thereabout by passing one eye through the other eye, laying the first eye against the body of said flexible member, forming a bight in said member adjacent said first eye, forming an eye in said bight by twisting, and twisting the shank of said first eye with the shank of said bight eye, and sealing means comprising a strip of material passed through said eyes and about a single portion of said member and means for sealing the strip of material.

In witness whereof, I hereby affix my signature this 19th day of September, 1924.

JOHN L. DINSMOOR.
